UNITED STATES PATENT OFFICE.

ELMER W. FERGUSON, OF NEW HAVEN, CONNECTICUT, ASSIGNOR TO CONNECTICUT CHIROPRACTORS' ASSOCIATION, OF NEW HAVEN, CONNECTICUT.

DESIGN FOR AN AUTOMOBILE RADIATOR EMBLEM.

Application filed June 25, 1928. Serial No. 27,282. Term of patent 7 years.

To all whom it may concern:

Be it known that I, ELMER W. FERGUSON, a citizen of the United States, and a resident of New Haven, in the county of New Haven and State of Connecticut, have invented a new, original, and ornamental Design for Automobile Radiator Emblem, of which the following is a specification, reference being had to the accompanying drawings, forming a part thereof.

Figure 1 is a plan view of my automobile radiator emblem, and

Figure 2 is an edge view.

I claim:

The ornamental design for an automobile radiator emblem, as shown.

ELMER W. FERGUSON.
